GRAIN DRIER

Charles D. Figley, 1266 4th Ave. SE, Cedar Rapids, Iowa
Filed Nov. 23, 1959, Ser. No. 854,736
5 Claims. (Cl. 34—56)

This invention relates to improvements in grain driers and includes as one of its objects the provision of an improved drier column construction designed to assure an even flow of air through the grain throughout the entire column.

Another important object contemplated herein is the provision of a variable speed metering wheel for controlling the speed of discharge of the grain from the drier column.

A further object is to regulate the speed of the metering wheel by a temperature sensing element disposed in the path of hot air flow in one of the column sections.

Further objects and the more obvious advantages of this invention will be mentioned or else appear plainly from the description which follows.

This invention consists of novel parts and combination of parts to be hereinafter described whereby the objects set forth are attained, as pointed out in the claims, and illustrated in the accompanying drawings, in which:

FIG. 1 is a side perspective view of this drier column showing in outline an adjacent house or enclosure for the blowers, heater and other control apparatus,

FIG. 2 is a top plan view of this drier partly cut away to more clearly indicate the construction of the column sections,

FIG. 3 is a longitudinal sectional view of this drier taken on the line 3—3 of FIG. 2,

FIG. 4 is an enlarged fragmentary perspective view of a lower column section to illustrate the metering wheel,

FIG. 5 is a cross sectional view taken on the line 5—5 of FIG. 4, and

FIG. 6 is a reduced schematic view taken from the line 6—6 of FIG. 3 to illustrate the connection between the controls for the metering wheel and the sensing element in the column.

Referring to the drawings, I provide a plurality of foundation pedestals or blocks 10, preferably of concrete or the like, which are in spaced relationship in a circular pattern and including a support block 12 of similar construction but slightly larger in bearing surface which is disposed under the front portion of the column as will later appear. Each block 10 supports a vertically disposed leg designated generally by the numeral 14 which is suitably anchored thereto. Legs 14 are V-shaped in cross section, having the diverging sides 16 and 18 with the apex end 20 disposed inwardly as shown in FIG. 2. At the lower end of each leg 14 on opposing faces of leg sides 16 and 18, there is secured an upstanding reinforcing member 22 of channel material or the like. Block 12 carries a vertically disposed modified U-shaped panel 24 (FIG. 2) which serves as the closure for the front of the drier column 26 and includes the center section 28 with angularly disposed sides 30 and 32 at respective opposite ends of block 12. The outer end of each side 30 and 32 terminates in the respective angularly projecting flanges 34 and 36 to which sides of the control house or shed 38 may be secured. Thus arranged, sides 16 and 18 on adjacent legs 14 define vertically disposed parallel spaced supports to which the column members 40 are mounted as will be described. Likewise, side 30 on panel 24 is similarly positioned relative to side 16 on leg 14 in a counter-clockwise direction, and side 32 on panel 24 has the same relationship to side 18 on leg 14 in a clockwise direction.

Each column member 40 defines a vertically disposed inner passageway or chamber 42 for the downward flow of grain and an adjacent chamber or passageway 44 for the

2

flow of air (FIG. 2). Chambers 42 and 44 are preferably rectangular in cross section. The inner side of chamber 42 is defined by a mesh screen wall 46, the outer side of chamber 44 by a solid weather shield panel of sheet metal or the like 48, and the two chambers are divided by a partition 50 of wire mesh screen. The screening 46 and 50 and weather shield 48 for each column member 40 are suitably secured as by brackets or the like 52 between adjacent leg sides 16 and 18 of adjacent legs 14 as above indicated. Column members 40 are formed in a series of vertically arranged column sections 54 (FIG. 3) whereby the entire drier column structure 26 can be made to variable height specifications with each column member 40 forming one of the sides of the assembled unit 26. Thus arranged, the several column members 40 together with the front panel 24 provide a central enclosed air chamber divided by floor 56 (FIG. 3) into the upper hot air chamber 58 and the lower cold air chamber 60. Floor 56 is positioned so that the hot air chamber 58 represents approximately two-thirds of the center air chamber in column 26. The front panel 24 is provided with vertically spaced openings 62 and 64 into the respective chambers 60 and 58 for communication with the respective hot and cold air blowers 66 and 68 in house 38 as shown in FIG. 1. No invention is claimed in blowers 66 and 68 and they are shown in outline only to illustrate their general relationship to column 26. The upper and lower weather shields 48a and 48b respectively on each column member 40 are hinged for opening to serve as vents for air chamber 44 and as seen in FIG. 1, the upper shield 48a is hinged at the bottom 49 to open outwardly from the top and the lower shield 48b is hinged at the top 49a to open outwardly from the bottom.

The bottom of the cold air chamber 60 is defined by a solid floor 70 and supports a hopper 72 in communication with the grain chambers 42 of the respective column members 40. The outlet end 74 will be spaced above the supporting surface for the block members 10 and 12 and may be connected with any suitable conveyor or the like for carrying the grain to a point of deposit. The top of the hot air chamber 58 is covered by an inverted cone-shaped closure 76 which serves as a garner floor in cooperation with the similarly shaped roof 78 disposed in vertical spaced relationship thereto and suitably supported by legs 14. A fill pipe 80 is carried at the apex of roof 78 and as grain is moved therethrough it is deflected by the garner floor 76 into the chambers 42 for movement downwardly to hopper 72. Air from chambers 58 and 60 moves through the moving grain by passing through screens 46 and 50 into chamber 44 where the hot air from chamber 58 is vented out the upper open weather shield 48a and cold air from chamber 60 is vented out the open lower weather shield 48b in the respective column members 40. It will be understood that the grain moves by gravity down chambers 42, which is a common arrangement in driers of this type, and experience has demonstrated that under certain conditions of humidity and temperature the grain may not always have obtained the desired degree of dryness when it reaches the outlet of the column. Some devices compensate for this by means to re-run the grain through the drier, but I have eliminated the problem by a metering assembly 82 (FIGS. 3 and 5) at the bottom or discharge end of chambers 42 by which the rate of discharge of the grain into hopper 72 can be controlled in relation to temperature and humidity conditions within the column 26. This is accomplished as follows.

At the bottom of each column member 40 there is a metering chamber 84 (FIG. 5) having a restricted opening 86 for communication with the grain chamber 42. Opening 86 is defined by a baffle 88 extending downwardly and outwardly from the lower inner side of chamber 42 to the

floor 70 and by another baffle 90 extending downwardly and inwardly from the lower outer end of chamber 42 to a point spaced above floor 70. These baffles extend transversely of the chamber 42 and baffle 90 is provided with an outwardly projecting flange or lip 92 (FIG. 4) extending between and secured to adjacent leg sections 16 and 18 on adjacent legs 14. The bottom of the metering chamber 84 is defined by a bottom plate 94 loosely attached at one edge to baffle 88 at point 96 so as to be susceptible of a slight hinge action and on the other edge carries a hook 98 that is yieldingly engaged by a spring or the like 100 connected to lip 92. Preferably two such springs (FIG. 4) are used for each chamber 84. This permits plate 94 to yield downwardly as grain passes over it into hopper 72.

An elongated paddle-type metering wheel 102, preferably with five spaced radially projecting blades, is disposed at the bottom of each column member 40 and transversely of the longitudinal axes thereof as shown in FIG. 4. Each wheel 102 is mounted on a shaft 104 for rotation therewith. Such shafts 104 are all driven from a single source of power located at the lower end of the front panel 24 (FIG. 2), which will be later described in detail, and for this purpose are connected as follows. As noted in FIG. 2, my column 26 is preferably made up of six column members or sides 40 and the front side represented by panel 24. Thus, in a counterclockwise direction from panel 24, shafts 104 in the three column members 40 to point 106 are connected by respective universal joints 108 located in the V opening of each leg 14, and in the opposite direction the other three shafts 104 are similarly connected.

To operate shafts 104, I use several commercially available devices arranged to produce the improved operation of this drier and since no invention is claimed in such devices per se, they are shown only diagrammatically although their function and operation will be explained. With reference now more particularly to FIGS. 2, 3 and 6, a variable speed hydraulic drive or transmission 110 is driven from one end by a belt drive 112 connected to an electric motor 114 and both may be mounted on a suitable platform or base 116. While the capacity of motor 114 may be varied, I have found that one-quarter or one-third horsepower is adequate. Such motor runs at a constant speed and through the transmission 110 drives shaft 118 on the other end of the transmission. Lever means 120 on the transmission 110 is arranged in a well known manner so that by appropriate movement thereof, the speed of shaft 118 can be varied. Shaft 118 carries a sprocket 121 which connects by chain drive 122 to a sprocket 124 on a jack shaft 126 suitably attached to side 30 of the front plate 24 and shaft 126 carries another sprocket 128 which connects by chain drive 130 to sprocket 132 on the drive shaft 134. Shaft 134 on respective opposite sides of sprocket 132 is operably connected to the respective two sets of three connected shafts 104 above described. In this way the two sets of connected shafts 104 which together define a generally circular path are operated by a single source of power emanating from a central point. Wheels 102 turn with shafts 104 and as shown in FIG. 5, wheels 102 are positioned to regulate and control the flow of grain from chambers 42 through openings 86 to the hopper 72.

One of the important objects herein is to control the passage of grain from chambers 42 so that it will be properly dried as it moves through openings 86 and to accomplish this, the speed of rotation of wheels 102 is regulated by a temperature sensing element 136 disposed in chamber 44 of one of the column members 40 just above the floor 56 (FIG. 3). Element 136 connects by leads 138 and 140 to a control switch 142 which is connected by the three leads 144, 146 and 148 to what is known as a modutrol motor 150 having a reversible shaft 152. Changes in temperatures affecting element 136 are reflected in the actuation of switch 142 which will

control the rotation of shaft 152 in two opposite directions respectively depending upon which two of wires 144, 146 and 148 are in circuit. Shaft 152 carries a link arm 154 secured thereto at one end for rotation therewith and pivotally secured at the other end to link member 156. The other end of link 156 is pivotally secured to lever 120 and by this linkage assembly described, it will be appreciated that operation of shaft 152 responsive to element 136 will correspondingly move lever 120 to increase or decrease the speed of rotation of shaft 118 and thus correspondingly change the speed of rotation of shafts 104 carrying the metering wheels 102. Motor 150 is connected by leads 158 and 160 to a source of electrical power (not shown).

15 By locating element 136 in the air flow chamber 44 of one of the columns 40 it operates in response to temperature changes in air coming off of the grain in chamber 42 and since humidity will affect the accurate temperature reading, element 136 in controlling the operation of 20 the metering wheel 102 will reflect the effect of the humidity at a point outside of the grain chamber 42. This has proved to be more satisfactory in discharging the grain with the desired moisture content than a 25 temperature sensing element in chamber 42 or 58 where actual temperatures are not always the same as outside of such chambers.

It is submitted that the invention shown and described is aptly suited to achieve the purposes intended and is characterized by a combination of highly useful and 30 mutually cooperating elements that combine their respective and proportionate functions in accomplishing the objects sought to be obtained.

It will be understood that the phraseology employed herein is for the purpose of description and not for limitation and that modifications and changes in the construction and arrangement of this invention can be made within the scope of what is claimed, without departing from the spirit and purpose thereof. It is thus intended to cover by the claims, any modified forms of structure or mechanical equivalents which may be reasonably included within their scope.

I claim:

1. In a grain drier construction, a vertically disposed front panel, a plurality of vertically disposed substantially rectangular column members disposed in a generally curved path and extending from one side of said panel to the other, means supporting said column members, each column member angularly disposed relative to an adjacent column member at an angle greater than ninety degrees, means in each column forming a grain flow chamber and an air flow chamber, vent means in said air flow chamber, a shaft transversely disposed at the bottom of each column member and rotatably mounted, a metering wheel on each shaft for rotation therewith, said metering wheels disposed to control the flow of grain from said respective grain flow chambers, universal joint means connecting the shafts in one series of contiguous column members into one drivable unit, the shafts in another series of contiguous column members similarly connected, said two series comprising all of said columns, a variable speed motor means operably connected to both drivable units for simultaneously rotating the shafts therein, a speed control means on said motor means, an electrically operated reversible motor operably connected to said control means, and a temperature sensing element in one of said air flow chambers electrically connected to said control means, and said control means being actuated in response to changes in said sensing element to increase the speed of rotation of said metering wheels with temperature increases and decrease the speed of rotation with temperature decreases.

2. In a grain drier construction, a plurality of foundation block members in a spaced circular pattern, a vertically disposed leg supported on each block member, a support block intermediate and spaced from two of said

block members as a part of said circular pattern, a vertical panel of U-shaped cross section carried by said support block to define a front side, a respective column member in the space intermediate each adjacent pair of said legs and secured at opposite edges to adjacent legs and with two of said columns secured at one respective edge to respective opposite sides of said panel to define side members and form a central air chamber, a bottom floor in said chamber, an intermediate floor therein spaced above said bottom floor to divide said air chamber into an upper hot air chamber and a lower cold air chamber, said column members each having an inner wire mesh wall, a solid outer wall serving as a weather shield, and a wire mesh partition wall intermediate said inner and outer walls, the zone intermediate said inner wall and partition defining a grain flow chamber, the zone between said outer wall and partition defining an air flow chamber, air vents at the lower and upper ends of said outer wall, said hot air chamber adapted to receive a forced hot air flow, said cold air chamber adapted to receive a cold air flow, an inverted cone-shaped garner enclosing the top of said central air chamber and designed to direct the flow of grain into said respective grain flow chambers, a roof over said garner, a fill pipe in said roof, a hopper at the bottom of said columns communicating with said grain flow chambers, a metering chamber at the bottom of each column member forming a grain discharge opening in the grain flow chamber, a rotatable paddle-type metering wheel in each metering chamber adapted to rotate across said discharge opening to permit the discharge of grain therefrom, an electrically operated variable speed means operably connected to said wheels for rotating the same, means responsive to temperature in one of said air flow chambers and operably connected to an electrical control switch, said switch being actuated by said temperature responsive means and operatively connected to said variable speed means for activating the same whereby the speed of rotation of said wheels is respectively increased or decreased according to respective increases or decreases in temperature in said air flow chamber.

3. In a grain drier construction, a plurality of foundation block members in a spaced circular pattern, a vertically disposed leg supported on each block member, a support block intermediate and spaced from two of said block members as a part of said circular pattern, a vertical panel of U-shaped cross section carried by said support block to define a front side, a respective column member in the space intermediate each adjacent pair of said legs and secured at opposite edges to adjacent legs and with two of said columns secured at one respective edge to respective opposite sides of said panel to define side members and form a central air chamber, a bottom floor in said chamber, an intermediate floor therein spaced above said bottom floor to divide said air chamber into an upper hot air chamber and a lower cold air chamber, said column members each having an inner wire mesh wall, a solid outer wall serving as a weather shield, and a wire mesh partition wall intermediate said inner and outer walls, the zone intermediate said inner wall and partition defining a grain flow chamber, the zone between said outer wall and partition defining an air flow chamber, air vents at the lower and upper ends of said outer wall, said hot air chamber adapted to receive a forced hot air flow, said cold air chamber adapted to receive a cold air flow, an inverted cone-shaped garner enclosing the top of said central air chamber and designed to direct the flow of grain into said respective grain flow chambers, a roof over said garner, a fill pipe in said roof, and a hopper at the bottom of said columns communicating with said grain flow chambers.

4. In a grain drier construction, a plurality of vertically disposed spaced legs arranged in a circular pattern, a vertical panel intermediate two adjacent legs defining a front side, a respective column member in the space intermediate each adjacent pair of the said legs and secured at op-

posite edges to adjacent legs and with two of said columns secured at one respective edge to respective opposite sides of said panel to define side members and form a central air chamber, a bottom floor in said chamber, an intermediate floor therein spaced above said bottom floor to divide said air chamber into an upper hot air chamber and a lower cold air chamber, said column members each having an inner foraminous wall, an outer solid wall and an intermediate foraminous wall, said foraminous walls defining a grain flow chamber and said outer wall and intermediate wall defining an air flow chamber, air vents in said outer wall, garner means at the top of said central air chamber, hopper means at the bottom thereof, a metering chamber at the bottom of each column member forming a grain discharge opening in the grain flow chamber, a rotatable paddle-type metering wheel in each metering chamber adapted to rotate across said discharge opening to permit the discharge of grain therefrom, an electrically operated variable speed means operably connected to said wheels for rotating the same, means responsive to temperature in one of said air flow chambers and operably connected to an electrical control switch, said switch being actuated by said temperature responsive means and operatively connected to said variable speed means for activating the same whereby the speed of rotation of said wheels is respectively increased or decreased according to respective increases and decreases in the temperature in said air flow chamber.

5. In a grain drier construction, a vertically disposed front panel, a plurality of vertically disposed substantially rectangular column members disposed in a generally curved path and extending from one side of said panel to the other, means supporting said column members, means dividing each column to form a grain flow chamber and an air flow chamber, vent means in said air flow chamber, a shaft transversely disposed at the bottom of each column member and rotatably mounted, a metering wheel on each shaft for rotation therewith, said metering wheels disposed to control the flow of grain from said respective grain flow chambers, universal joint means connecting the shafts in one series of immediately adjacent column members into a single drivable unit, the shafts in the other immediately adjacent column members similarly connected, said two series comprising all of said columns, a single source of power operably connected to both drivable units for simultaneously rotating the shafts therein, electrically actuated variable speed transmission means operably connected to said shafts for varying the speed of rotation thereof, an electric control switch connected to said variable speed transmission means, and means responsive to temperature in one of said air flow chambers and electrically connected to said control switch for actuating the same according to predetermined settings to respectively increase or decrease the speed of rotation of said shafts according to respective increases or decreases in temperature.
